UNITED STATES PATENT OFFICE.

ALFRED B. WALKER, OF CINCINNATI, OHIO, ASSIGNOR TO FRANK W. WILSHIRE, OF SAME PLACE.

FURNACE:

SPECIFICATION forming part of Letters Patent No. 674,129, dated May 14, 1901.

Application filed April 28, 1900. Serial No. 14,665. (No model.)

To all whom it may concern:

Be it known that I, ALFRED B. WALKER, a citizen of the United States, residing at Cincinnati, in the county of Hamilton and State of Ohio, have invented certain new and useful Improvements in Furnaces, of which the following is a specification.

My invention relates to that class of furnaces which employ an endless-belt grate.

10 One object of my invention is to improve the general construction of the furnace, so as to secure a perfect combustion, and also to provide a construction of the furnace that coke, hard coal, or bituminous coal may be 15 completely consumed in the same and without producing smoke.

Another object of my invention is to provide an improved chain of endless grate-bars, each of which will revolve slowly in its action, 20 so as to prevent an undue heating of the bars.

The various features of my invention will be more fully set forth in the description of the accompanying drawings, forming a part of this specification, in which—

25 Figure 1 is a central vertical section of my improved furnace. Fig. 2 is a front elevation, partly in section, of Fig. 1 with the feed-hopper-removed. Fig. 3 is an enlarged side elevation of my improved endless grate-bars and 30 driving mechanism. Fig. 4 is a top plan view of the same. Fig. 5 is a perspective view of one of the links which carry the grate-bars. Fig. 6 is a modification of Fig. 3.

In the drawings, A represents the front wall 35 of the furnace; B, the rear wall; C, the hopper of the feed-chute, which forms a primary combustion-chamber.

D represents the breast of the chimney.

E represents the endless chain of grate-bars.

40 F G represent sprocket-drums for propelling the endless-chain grate-bars, one of which is driven by a suitable motor.

H represents air flues or ducts leading through the front wall of the furnace for supplying air to the air-heating chamber I under the endless grate.

J represents the mouth or opening leading from the feed-chute into the combustion-chamber K.

In order that the grate-bars may not be unduly heated on one side and warp, I make these grate-bars hollow and of sufficient size to allow a free circulation of air through them. I also employ the following devices for slowly revolving them in their forward travel under the combustion-chamber.

L represents one of the chain-links. In the preferred form of construction there are three of these tubular grate-bars journaling in the side bar a', which is rigidly secured to one of the members of the links a.

The links a a are hinged together in a suitable manner. They are provided with an opening b to receive the teeth on the sprocket-drums, so as to propel the endless chain of 65 grate-bars.

M represents a rack-bar. It is shown in Fig. 2 supported under the jamb M' and at one side of the combustion-chamber.

N represents gear-teeth, preferably cast on 70 the hollow grate-bars at one end. These teeth engage with those of the rack-bar, which cause the tubular grate-bars to revolve as they are propelled forward along their upper longitudinal path. The rack-bar may be suspended 75 either above or below the grate-bars, as shown in Fig. 2 or Fig. 6.

O represents a water-tube which spans the bottom of the arch at the mouth or feed-opening into the furnace at the heat side thereof, 80 where the arch is subjected to the greatest heat, so as to prevent the bricks from being broken by the contact of the fuel against the arch as it is forced into the furnace by the traveling grate.

85 Mode of operation: The feed-hopper is filled with fuel. Kindling is placed in the mouth J. This kindling is ignited, and the fuel is raised to the regular degree of heat before the endless chain grate is set in motion. The 90 incandescent fuel at the mouth of the combustion-chamber is slowly carried across said chamber. The rate of speed of the traveling grate is such that the fuel is not carried into the combustion-chamber any faster than it 95 is brought into a state of incandescence and is completely consumed by the time it reaches the rear end of the chamber.

It will be observed that the fuel moved out of the bottom of the chute or hopper by means of the traveling fuel-bed carries the top of the fuel layer against the sharp stoking-abutments 1 2 3 4 of the arch, thereby acting upon the successive layers of green fuel, serving to turn it over away from the passage J. This insures that the heat will reduce the fuel to an incandescent state by the time it has been turned over and over and finally reached the bottom of the chute, so that no green fuel passes into the chamber K. This arch has a stoking function which might be produced in a less degree with but the single arch formed so as to push back the top fuel layer; but the form shown is preferred. These sharp corners perform a further function. They become highly heated. The air is drawn through the fuel in the chute and commingles thoroughly with the products liberated therein by the heat in such manner as to make a most perfect mixture. This mingled gas and air rises to the top and is impinged against these highly-heated sharp abutments, which serve, as it were, also as fixing-chambers, chemically uniting and igniting the mechanically-mixed air and gas so that these gases literally shoot out into the chamber K through passage J in a flame, the color of which indicates a perfect combustion. If the gases are not all consumed at this point, they are passed over the incandescent fuel on the traveling bed in the oxidizing superheated zone created in chamber K and consumed perfectly therein. It is obvious that this passing of the products evolved from the green coal in one compartment over the constantly-moving incandescent bed in another chamber, where it is subjected to the chemical action of highly-heated air, will burn any smoke formed.

The process of "stoking" incident to the management of the furnace aims to keep a fresh incandescent fuel-bed for consuming the smoke from the green fuel. It is obvious that my device automatically and perfectly stokes the fuel, rendering it impossible to "smother" the fuel-bed, thoroughly uniting the air and gases in a highly-heated state, and sifting out the ash as fast as it is formed instead of letting it accumulate and dumping it at the end of the travel or other stated intervals, and so giving the most favorable conditions for a complete combustion of fuel.

When coarse fuel is used, a large amount of air will pass into the furnace through this coarse fuel, and it will be heated before it enters into the combustion-chamber. The air which enters through the ducts H becomes heated in the chamber below the traveling grate, and as it passes between the grate-bars it becomes highly heated and is in proper condition to support the combustion without the cooling of the incandescent gases driven from the fuel.

In the drawings is shown a large combustion-chamber above the traveling grates; but this form is not material. It may be adapted to a steam-boiler or to a reducing or a heating furnace, and its form will be variously modified, according to the uses for which it is to be employed.

Having described my invention, I claim—

1. In a furnace, a combustion-chamber, a traveling grate, a stoking device above said grate having offsets adapted to engage and agitate the fuel presented to it by the traveling grate, and means for operating said grate, substantially as described.

2. In a furnace employing an endless-traveling-belt grate driven by drums and located under the feed-chute and combustion-chamber, said endless grate being provided with grate-bars and mechanism for revolving the said grate-bars individually as they are propelled forward by the revolution of the drums, substantially as specified.

3. In a furnace employing an endless traveling grate, a primary chamber and a combustion-chamber located above said grate and communicating with each other, an arch downwardly inclined in the direction of the movement of the grate, provided with a series of offsets, and means for revolving said grate, substantially as and for the purpose specified.

4. In a furnace the combination with the drums and an endless traveling chain grate propelled by the same, said chain grate composed of links having plate extensions in which are journaled hollow grate-bars, substantially as specified.

5. In a furnace, the combination of an endless-chain grate, suitable drums engaging and propelling said chain, revolving grate-bars journaled in the chain-links and provided with gear-teeth meshing with a rack-bar in the furnace whereby the grate-bars are continuously revolved as they progressively move through the furnace, substantially as specified.

6. In a furnace, the combination of a primary chamber, and a combustion-chamber located over a traveling grate, a stoking device forming the partition between said compartment and chamber and adapted to crowd back the top layers of fuel into said feeding compartment, and means for supplying air to said combustion-chamber, substantially as specified.

7. In a furnace employing a traveling grate, the combination of a primary chamber and a combustion-chamber located over said grate, a partition between said chambers forming a passage under the partition, one or more stoking devices formed on the face of said partition in the chute-chamber, and means for feeding air to the combustion-chamber, and means for actuating said grate, substantially as specified.

3. In a furnace, the combination of a feed-chamber and a combustion-chamber, a revolving grate mounted on drums under said chamber, means for passing the ash through said grate during its travel, a stoking-partition between said chambers over the grate forming a passage between them, an offtake-flue in the combustion-chamber; and means for sup-

plying air thereto and revolving said grate, substantially as specified.

In testimony whereof I have hereunto set my hand.

ALFRED B. WALKER.
